Patented Sept. 13, 1921.

FIG. 1.

FIG. 2.

FIG. 3.

Inventor

G. Lawler,

By H. R. Henslape.

Attorney

UNITED STATES PATENT OFFICE.

GEORGE LAWLER, OF AUCKLAND, NEW ZEALAND.

HEEL-GRIP FOR SHOES.

1,390,568.

Specification of Letters Patent. Patented Sept. 13, 1921.

Application filed August 26, 1920. Serial No. 406,253.

To all whom it may concern:

Be it known that I, GEORGE LAWLER, a citizen of the Dominion of New Zealand, and residing at 123 Remuera road, Remuera, in the Provincial District of Auckland, New Zealand, a subject of the King of Great Britain and Ireland, have invented certain new and useful Improvements in an Improved Heel-Grip for Shoes, of which the following is a specification.

This invention relates to shoes, especially ladies' shoes, and provides improved means for preventing same from slipping at the heel when being worn.

The invention consists in providing a pneumatic pad, shaped to fit and adapted to be secured vertically around the inside of the back portion of a shoe, the lower edge of the pad being recessed or shaped to accommodate the back of the wearer's heel, in order that the latter will be firmly gripped by the pad, and the shoe prevented from slipping and chafing the heel when walking.

The invention will be further described with reference to the accompanying drawing in which,

Figure 1, is a perspective view of the rear portion of a shoe, showing the pad fitted therein.

Fig. 2, is a view of the pad opened removed from the shoe and,

Fig. 3 is a cross sectional view of same.

The pneumatic pad 1 is made the shape shown in Fig. 2 and consists in two normally spaced walls connected around the margin of the pad as shown in Fig. 2. A strip 2 of canvas, strong calico webbing or the like, is secured along the upper edge of the pad so as to project from same.

The lower edge of the strip 2 is attached to the pad 1 by a rubber solution or other suitable adhesive matter, or may be embedded in the rubber or other material from which the pad 1 is formed.

The pad 1 is bent and placed vertically in the rear portion 3 of the shoe as shown

and is secured by the strip 2 being bent downward and glued to the inside of the heel portion 3, or between the thicknesses of leather of the latter.

The pad 1 can also be secured to the portion 3 by adhesive matter.

The pad is made of a greater depth at its ends than at its center, so as to form a central recess 4, which accommodates and grips the back of the heel of the wearer of the shoe when the latter is being worn.

Also the pad 1 being pneumatic is resilient and compresses sufficiently to allow the shoe to be put on and taken off with ease. Immediately however, the shoe is in position on the foot, the pad expands and firmly grips the heel.

What I do claim and desire to secure by Letters Patent of the United States is,

1. A heel grip for shoes comprising a flat pad having an internal fluid-tight air chamber providing a pneumatic cushion, said pad being adapted to be secured about and to cover the major portion of the heel of a shoe.

2. A heel grip for shoes comprising a flat pad having an internal fluid-tight air chamber of uniform thickness throughout embodying a pneumatic cushion, said pad being adapted to be secured about and to cover the major portion of the inner heel portion of a shoe.

3. A heel grip for shoes comprising a flat pad having an internal fluid-tight air chamber normally of uniform thickness throughout and having the terminal portions of the pad increased in width, said pad being adapted to be fitted and secured about the inner portion of the edge of a shoe.

In testimony whereof I affix my signature in presence of two witnesses.

GEORGE LAWLER.

Witnesses:

LOUIS WILFRED HOLLIS HILL,
GEORGE SHEWARY.
